UNITED STATES PATENT OFFICE.

THOMAS V. ALLIS, OF NEW YORK, N. Y.

METALLIC-STRIP BLANK FOR BARBED FENCING.

SPECIFICATION forming part of Letters Patent No. 272,933, dated February 27, 1883.

Application filed August 23, 1881. Renewed March 8, 1882. Again renewed September 21, 1882. (No model.)

To all whom it may concern:

Be it known that I, THOMAS V. ALLIS, of the city, county, and State of New York, have invented a new and useful Improvement in 5 Metallic-Strip Blanks for Barbed Fencing, of which the following is a specification.

This invention consists of an improved manufacture of ribbed metallic-strip blanks for making barbed fencing by partially severing 10 the ribs from the strips and bending them so as to form projecting barbs.

The improvement consists of the said ribbed strips, having a groove or crease in the sides of the ribs along the surface of the strips where 15 said ribs join the strips, making the ribs thinner thereat than they are outwardly, to improve the barbs made therefrom both in form and condition, and to facilitate the cutting of the ribs to form the barbs, all as hereinafter 20 described, reference being had to the accompanying drawings, in which—

Figure 1 is a top view of the improved ribbed metallic-strip blank of my invention. Fig. 2 is a side elevation of the same. Fig. 3 25 is a cross-section of the rod, showing the form to which I reduce it preparatory to making the ribs. Fig. 4 is a cross-section of the strip through one of the ribs when partially formed. Fig. 5 is a cross-section through the rib when 30 the rod is completed. Fig. 6 is partly a side elevation and partly a section of the rolls I employ for the manufacture of the said improved blank-strip. Fig. 7 represents the said rolls in side elevation. Fig. 8 represents a 35 top view of the barbed strip after the barbs have been formed, and Fig. 9 is a side view of the same when twisted and completed.

The flat strip B, with oval edges, and having short longitudinal ribs A, with pointed 40 ends, along one or more sides, at certain predetermined distances apart, and being creased or grooved, at C, along their junction with the strip B, constitutes the improved blank of my invention, said blank being for the manufacture of barbed fencing by cutting said ribs 45 from the strip at one or both ends along the same toward but not to the middle, and bend-

ing them into the form of projecting barbs D, Figs. 8 and 9. I make this blank by drawing or rolling a rod of round or other form into 50 the triangular form represented by the cross-section, Fig. 3, then pass it through the collar and groove-rolls E F, having flat passes except where the recess G is formed in the bottom of the groove, wherein the rod is flattened on one of the angles except where the recess G passes, leaving ribs in the form represented in Fig. 4. From rolls E F, I cause the 55 ribbed strips to pass between the creasing-rolls H, having grooves I and creasing-die 60 collars J, which form the creases C. After thus forming the ribbed strip, I cut or shear the ribs from the points along the strip a suitable distance for the length of the barbs, and bend them laterally thereto, and finally twist 65 the strip, as represented in Fig. 9, to cause the barbs to point in different directions. By creasing the ribs along the strip, as represented, the form of the resulting barb is greatly improved, also the quality, as compared with 70 barbs made from ribs not so creased, as in Fig. 4, because the crease makes them partially round and less angular on the side cut from the strip. The cut is smoother, less cut surface is exposed, and the condition of the barb 75 in respect to its solidity is much better, for where the thickness of the rib is equal at the line of cutting to the rest the tendency to crack, split, splinter, and curl is greater. There is also a material economy in the wear and cost 80 of the mechanism employed for cutting and bending the barbs.

Having thus described my invention, what I claim, and desire to secure by Letters Patent, 85 is—

The improved ribbed metallic-strip blank for barbed fencing herein described, consisting of the flattened strip B, with ribs A along the surface of the same, creased or grooved in their sides along the strip, substantially as described. 90

THOMAS V. ALLIS.
